UNITED STATES PATENT OFFICE

WILLIAM F. BRÜGMANN, OF EVANSTON, ILLINOIS

PRINTER'S REGISTER HOOK

Application filed August 29, 1927. Serial No. 216,006.

This invention relates to improvements in body portion of the hook with all parts, re-printers' register hooks and bases, and has for one of its objects to improve and simplify the construction, and at the same time produce a hook of great strength and one that will be fast in operation.

Hitherto all hooks known as "limited distance" hooks have the inherent fault that whenever the hook has reached the full limit of its action, it must be returned to its initial point of operation through the same mechanical medium as that by which it was advanced.

When it is considered that in a thirty-two page form there are one hundred and ninety-six hooks necessary, it can be readily seen that much time is consumed in the process of restoring hooks to their initial position.

To overcome these difficulties and objections and to provide an improved hook, which can, when the limit of action has been reached, be readily put back or restored to the initial position independently of the means by which it was advanced is another object of the present invention.

To the attainment of these ends and the accomplishment of other new and useful objects as will appear the invention consists in the features of novelty in substantially the construction, combination and arrangement of the several parts hereinafter more fully described and claimed and as shown in the accompanying drawings in which:

Figure 1 is a plan view of a base having a plate mounted thereon by hooks constructed in accordance with the principles of this invention.

Figure 2 is a detail sectional view taken on lines 2-2 Figures 1 and 3.

Figure 3 is a sectional view taken on line 3-3 Figure 1.

Figure 4 is a perspective view of the hook taken from one side thereof and showing the tools by means of which the jaw may be advanced or retracted.

Figure 5 is a perspective view of the hook taken from another side thereof.

Figure 6 is a detail sectional view taken on line 6-6 Figure 3.

Figure 7 is a detail perspective view of the

Figure 8 is a perspective view of the separating element for the body members.

Figure 9 is a perspective view of one of the body members.

The hook consists essentially of a main body portion 10, of any desired size and configuration and is provided with a recess 11, extending lengthwise therethrough and opening through one side thereof for the entire length of the body. The recess where it opens through the side of the body is reduced as at 12, to form overhanging shoulders 13, for a purpose to be set forth.

The wall of the recess opposite the lateral opening is provided with teeth 14, preferably shaped to form ratchet teeth which preferably terminate short of the bottom of the said body and the body portion is provided adjacent the lower end with an opening 15, extending through the side of the body opposite the first said lateral opening. A slot 16 is provided in the closed side of the recess in the body portion and through the said teeth 14, for a purpose to be set forth.

A member 17, is pivotally mounted by its lower end as at 18, to the lower end of the body portion 10, and within the said recess 11, and is adapted to be moved about its pivot 18, so that the free end thereof may be projected laterally beyond the said body portion 10, and a spring 19, is provided which tends normally to retract the said member 17.

If desired the member 17, may be provided with a shoulder 20, which engages under shoulders 21, on the body portion 10.

The member 17, may also be provided with a projection or formation 22, on its outer face, preferably adjacent the pivot 18, and the inner face of the member 17, is inclined or beveled as at 23, and the angle or pitch of said surface 23, may be of any desired cam formation to produce a uniform throw of the plate holding jaw 24, which is connected with the body member 10.

The outer surface of the member 17, may be rounded, if desired, so as to conform to the contour of the hole into which the hook is inserted in the base or mounting.

An element 24, having ribs or lugs 25, is preferably provided with a laterally projecting portion 26, at the base thereof and rotatably mounted upon said projection is a gear or worm 27, held in position preferably by reducing one end thereof as at 28^a, (see Figure 3) to be journaled in an opening in said projection.

A headed screw 29^a, passes into the end 10 of the said reduced portion and the diameter of the head of the screw is somewhat larger than the diameter of the said opening.

The upper end of the worm gear 27, preferably terminates substantially flush with the 15 top of the element 24, and is provided with a recess 28, opening through the top thereof.

This recess is angular in cross section to receive the angular extremity 29, of a tool 30, so that when the tool is rotated after being inserted into the recess 28, the gear or worm 27, will be rotated to advance or retract the element 24, by reason of the fact that the threads of the worm or gear engage and co-operate with the rack teeth 14.

25 The element 24, and worm or gear 27, are inserted into the body portion within the recess 11, and between the members 10, and 17, the lugs or ribs 25, passing under the overhanging shoulders 13, while a portion 30 of the element 24, will extend into the portion of the recess 11, which opens through the side of the body member 10.

The spring 19, not only serves to retract the member 17, but also operates to hold the 35 threads of the gear or worm 27, in contact with the rack teeth 14.

The surface of the plate holding or engaging jaw 24^a, which engages the edge of the plate 31, is rounded as at 32, so that when the 40 body member is inclined or rocked by the separation of the members 10, and 17, as hereinafter set forth, the surface 32, of the jaw will always have a proper bearing upon the edge of the plate and no portion of the 45 jaw will cut into the edge of the plate.

The jaw 24^a, is provided with a hole 33, in alignment with the opening 28, in the worm or gear 27, to permit of the insertion of the end 29, of the tool 30.

50 This form of hook is particularly adapted for use with a base 34, having round openings 35, therein and into which openings the hook is inserted so that the jaw 24^a, will move across the top of the base. The openings 55 taper from the top of the base as at 36, to a point spaced from the bottom of the opening and merges into a cylindrical portion 37, adjacent the bottom of the opening.

A channel or groove 38, is provided in the 60 wall of the opening and communicates with the opening. The channel or groove is so positioned that when the hook is inserted in the opening, the projection or formation 22, on the member 17, will enter the channel and 65 the hook will thereby be held against acci-

dental displacement or removal from the said opening in the base.

The diameter of the upper portion of the opening 35, is considerably greater than the external diameter of the body portion of the hook to allow the body portion to rock in said opening, and the portion 37, is of a diameter only slightly greater than the largest diameter of the lower end of the body of the hook which is seated therein so that when the body 70 of the hook is rocked in the opening 35, the edges of the lower portion of the hook will engage the wall of the portion 37, to form a stop to prevent any considerable movement of the lower end of the body of the hook, as 75 shown in Figure 6 of the drawings.

In operation the element 24, is positioned adjacent the jaw 24^a, and top of the body portion 10. The spring 19, will then hold the member 17, retracted with respect to the body 85 member 10.

The hook is then dropped into the opening 35, with the surface 32, of the jaw adjacent the edge of the plate 31. The hook will then preferably be located adjacent one side of 90 the opening 35, with the outer surface of the member 17, in contact with the wall of the opening.

The element 24, is then advanced lengthwise of the body member 10, and forced between the members 10, and 17, to separate them by swinging the member 17, about its pivot 18, against the stress of the spring 19. The outer face of the member 17, contacting with the wall of the opening 35, will rock the body member 10, the lower edge thereof being arrested in the rocking movement by contacting with the wall of the opening 37, thereby causing the surface 32, of the jaw to engage and rock over the edge of the plate 31, until the plate is securely clamped to the base 34.

The element 24 may be advanced and retracted with respect to the member 10, by inserting the end 29, of the tool 30, into the opening 28, of the worm or gear 27, and rotating the latter, or if a quick advancement of the element 24 is desired, it is only necessary to insert the tool 30, and press upon the element 24, to cause it to ratchet across the teeth 14, on the body member, after which the worm or gear 27, may be rotated to produce a micrometer adjustment.

To produce a quick return of the element 24, with respect to the body member 10, any 120 desired or suitable means may be provided for disengaging the threads of the worm or gear 27, from the rack teeth 14, thereby permitting the element to be bodily moved back to its initial starting position.

The preferred manner of accomplishing this result is illustrated in Figure 4 of the drawings in which there is provided a suitable tool or implement 38^a, one end of which may be inserted into the slot 16, when the 125

hook is removed from the recess in the base, to engage the worm or gear 27, and by exerting pressure upon the worm or gear in a direction transverse to its axis, the threads of the gear may be moved out of engagement with the rack teeth 14, the spring 19, and member 17, yielding under such pressure to permit the disengagement of the gear from the rack.

10. The element 24 and gear 27, may then be readily retracted or bodily moved backward as the gear will be maintained out of engagement with the rack teeth during such return movement of the element 24.

15. While the preferred form of the invention has been herein fully described and shown, it is to be understood that various changes may be made in the details of construction and in the combination and arrangement of 20 the several parts, within the scope of the claims, without departing from the spirit of this invention.

What is claimed as new is:

1. A printer's register hook embodying a body portion, a member carried thereby and adapted to be projected laterally beyond one side thereof, said member being maintained against movement lengthwise of the body, and a member movable lengthwise of said body portion for engaging and projecting the first said member, said member having an extended lateral face adapted to rest flat against the wall of an opening into which the hook is inserted.

35. 2. A printer's register hook embodying a body portion, a member carried thereby and adapted to be projected laterally beyond one side thereof, said member being maintained against movement lengthwise of the body, a member movable lengthwise of said body portion for engaging and projecting the first said member, said member having an extended lateral face adapted to rest flat against the wall of an opening into which the hook is inserted, and means tending normally to hold the first said member retracted.

50. 3. A printer's register hook embodying a body portion, a member carried thereby and adapted to be projected laterally beyond one side thereof, a member movable lengthwise of the said body portion for engaging and projecting the first said member, and means for moving the first said member lengthwise of the said body, the said means embodying interengaging ratchet teeth whereby the last said member may be given a return movement with respect to the said body independently of the first recited means.

55. 4. A printer's register hook embodying a body portion, a member carried thereby and adapted to be projected laterally beyond one side thereof, a member movable lengthwise of said body and adapted to engage and project the first recited member, and means for causing the second recited member to be advanced

with respect to said body, the last said means also operating to permit the second recited means to be returned independently of the said advancing means.

5. A printer's register hook embodying a body portion, a plate engaging jaw carried thereby, a rack on said body, and a gear mounted upon the body and engaging said rack, said gear being movable lengthwise of the body for advancing or retracting the jaw, the said gear being mounted for bodily movement out of engagement with the rack whereby the gear may be moved to its initial starting position with respect to the said body, independently of the said rack.

6. A printer's register hook embodying a body portion, a plate engaging jaw carried thereby, a rack on said body, and a gear mounted upon the body and engaging said rack, said gear being movable lengthwise of the body for advancing or retracting the jaw, the said gear being mounted for bodily lateral movement with respect to the rack whereby said gear may be caused to ratchet across the rack to advance the gear with respect to the body and independently of the rack.

7. A printer's register hook embodying a body portion, a member carried thereby and adapted to be projected laterally beyond one side thereof, an adjusting screw, and a non-rotatable member carried by the screw and movable upon the body for engaging and projecting the first said member, the contacting face of the first said member and the said operating member being both inclined.

8. A printer's register hook embodying a body portion, a member pivotally mounted thereupon and adapted to be swung about its pivot to project laterally beyond the side of the said body, resilient means tending normally to hold said member retracted, an additional non-rotatable member mounted upon said body and operating between the body and the first said member to swing the latter about its pivot, and means for advancing the said additional member.

9. A printer's register hook embodying a body portion, a member pivotally mounted thereupon and adapted to be swung about its pivot to project laterally beyond the side of the said body, resilient means tending normally to hold said member retracted, an additional member mounted upon said body and adapted to engage and move the first said member about its pivot, and means for advancing and retracting the said additional member, the last said means embodying provisions whereby the said additional member may be bodily retracted independent of the said advancing means.

10. A printer's register hook embodying a body portion, a member pivotally mounted thereupon and adapted to be swung about its pivot to project laterally beyond the side of the said body, resilient means tending nor-

- mally to hold said member retracted, an additional member mounted upon said body and adapted to engage and move the first said member about its pivot, and means for advancing the said additional member, the last said means embodying provisions whereby the said additional member may be bodily advanced independent of the said advancing means.
11. A printer's register hook embodying two members connected together, a plate holding jaw carried by one of the members, a screw, an element carried with the screw and with respect to which element the screw is rotatable, said screw mounted upon one of said members and for separating the members, and means tending normally to move said members together.
12. A printer's register hook embodying two members connected together, a plate holding jaw carried by one of the members, an element mounted upon one of the members and movable between the members for separating them, means for advancing and retracting the last said means, the said advancing and retracting means embodying provisions whereby the said element may be bodily moved in the direction of its advancing movement independently of the said advancing means, and means tending normally to retract the first said members with respect to each other.
13. A printer's register hook embodying two members connected together, a plate holding jaw carried by one of the members, an element mounted upon one of the members and movable between the members for separating them, means tending normally to move the said members together, and means whereby the said element may be bodily returned in its movement with respect to its mounting independently of the said advancing means.
14. A printer's register hook embodying a body portion, a member carried thereby and adapted to be projected laterally beyond one side thereof, an adjusting screw mounted upon the body portion, and a wedge shaped member carried by the screw and interposed between said body and the first said member and operable to separate them and with respect to which wedge shaped member the screw is rotatable.
15. A printer's register hook embodying a hollow body portion having an opening through one wall extending lengthwise of the body portion, teeth extending along the wall of said body, a member housed within said body portion and adapted to be projected laterally through said opening, and a screw member movable lengthwise of said body and having an extended contact with said teeth, said screw member being disposed between the first said member and the wall of said body portion and engaging both for sepa-

rating them, said screw being rotatable with respect to the second recited member.

16. A printer's register hook embodying a hollow body portion having an opening through one wall extending lengthwise of the body portion, a member housed within said body portion and adapted to be projected laterally through said opening, an adjusting screw carried with the said body, and an expanding member carried with the screw and movable between the first said member and the body portion for separating them and with respect to which expanding member the screw is rotatable.

17. A printer's register hook embodying a hollow body portion having an opening through one wall extending lengthwise of the body portion, a member housed within said body portion and adapted to be projected laterally through said opening, an adjusting screw carried with the said body, and an expanding member carried with the screw and movable between the first said member and the body portion for separating them, and with respect to which expanding member the screw is rotatable, the contacting faces of the said members being inclined.

18. A printer's register hook embodying a body portion, a member carried thereby and adapted to be projected laterally beyond one side thereof, and a non-rotatable expander member disposed between the first said member and said body portion and movable lengthwise of the body portion, the said members having extended inclined or beveled surfaces contacting with each other.

19. A printer's register hook embodying a body portion, a jaw member carried thereby, a locking member carried with the jaw member, and means for locking the jaw member in position and to move the jaw member into contact with a printing plate, the said means embodying an adjustment screw and a wedge member co-operating with the screw and with respect to which the screw is rotatable said wedge member being interposed between the said locking member and the jaw member and contacting with the locking member.

20. A printer's register hook embodying a body portion, a jaw member carried thereby, a locking member carried with the jaw member, and means for locking the jaw member in position and to move the jaw member into contact with a printing plate, the said means embodying an adjustment screw and a wedge member co-operating with the screw and with respect to which the said screw is rotatable, said wedge member being interposed between the said locking member and the jaw member and contacting with the locking member, the contacting faces of the wedge member and the said locking member being extended and inclined.

21. A printer's register hook embodying a body portion, a member carried thereby and

adapted to be projected laterally beyond one side thereof, and an adjusting screw mounted upon the body portion, and a wedge member contacting with the first said member and movable therealong and operating to separate the body portion and the first said member, said adjusting screw carried by the said wedge member and engaging the said body portion, said screw having an extended contact lengthwise of its axis with the wedge and said body portion.

22. A printer's register hook embodying a body portion, a member carried thereby and adapted to be projected laterally beyond one side thereof, and an adjusting screw mounted upon the body portion, a wedge member contacting with the first said member and movable therealong and operating to separate the body portion and the first said member, said adjusting screw carried by the said wedge member and engaging the said body portion, said screw having an extended contact lengthwise of its axis with the wedge and said body portion, said screw being partially housed in said wedge member.

23. A printer's register hook embodying a body portion, a member carried thereby and adapted to be projected laterally beyond one side thereof, and an expander member movable lengthwise of the body portion and operating to control the first said member, the expander member and first said member having extended inclined or beveled lateral surfaces engaging each other.

35 In testimony whereof I have signed my name to this specification, on this 25th day of August, A. D. 1927.

WILLIAM F. BRÜGMANN.
